[57] CLAIM

The ornamental design for a faucet spout, as shown and described.

DESCRIPTION

FIG. 1 is a perspective view of a faucet spout showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof, the left side view being a mirror image of the right side;

FIG. 7 is a perspective view of a faucet spout showing another embodiment of my new design;

FIG. 8 is a front elevational view of the faucet spout shown in FIG. 7;

FIG. 9 is a rear elevational view of the faucet spout shown in FIG. 7;

FIG. 10 is a top plan view of the faucet spout shown in FIG. 7;

FIG. 11 is a bottom plan view of the faucet spout shown in FIG. 7; and,

FIG. 12 is a right side elevational view of the faucet spout shown in FIG. 7, the left side view being a mirror image of the right side.

The broken lines in the Figures are for illustrative purposes only and forms no part of the claimed design.
